UNITED STATES PATENT OFFICE.

HAYES YOUNG, OF CABLE, OHIO, ASSIGNOR OF ONE-THIRD TO WILBERT YOUNG, OF SAME PLACE.

CARRIAGE-CURTAIN CATCH.

SPECIFICATION forming part of Letters Patent No. 610,374, dated September 6, 1898.

Application filed June 19, 1897. Serial No. 641,510. (No model.)

To all whom it may concern:

Be it known that I, HAYES YOUNG, residing at Cable, in the county of Champaign and State of Ohio, have invented a new and useful Carriage-Curtain Catch, of which the following is a specification.

This invention has relation to fastening devices for securing carriage-curtains.

An object of the invention is to provide a catch for carriage-curtains so constructed that the curtains can be fastened within the desired position in a very simple and effective manner.

A further object of the invention is to provide a catch for carriage-curtains, the parts thereof being so arranged that there will be no possibility of any of the several portions thereof pulling out from the body portion of said curtain or of any rattling of the several parts thereof.

A further object of the invention is to provide a catch for carriage-curtains composed of but a few strong and inexpensive parts and one that can be manufactured and placed in position without difficulty.

With these and other objects in view my invention consists in certain novel features of construction and in combinations and arrangements of parts, that will be hereinafter more fully described, and then specifically pointed out in the appended claim.

In order that my invention may be fully understood, I will now proceed to describe the same with reference to the accompanying drawings, in which—

Figure 1 is a perspective view of my device in operative position. Fig. 2 is a vertical sectional view on the line 2 2 of Fig. 4. Fig. 3 is a horizontal sectional view on the line 3 3 of Fig. 4. Fig. 4 is a front elevation. Fig. 5 is a general view of the fastening device, the several parts thereof being shown disassembled; and Fig. 6 is a detail view of a modified form of spring used in connection with my improved fastening.

The same letters of reference mark the same parts wherever they occur throughout the several views.

In carrying out my invention I have shown a base or body portion of a carriage A, the

same being adapted to receive a button or knob B, said knob or button having a pin formed integral with the rear portion thereof, so as to enter the base A of the carriage. This knob or button is provided with an enlarged portion near its front end, while the part thereof in front of the pin is somewhat reduced, so that when a curtain is fastened thereto it will be securely held in place, thereby preventing such curtain from slipping off of the same.

C indicates a washer or plate preferably circular in form and provided with the slots D, said plate being provided with a central opening E and adapted to bear against the rear portion of the curtain.

F represents a washer having the rearwardly-extending flange F', which is adapted to extend through the central opening of washer C, and with an annular flange on its opposite face which extends through the opening of the curtain. A washer I, having the central opening J and the holes K, which register with the slots of washer C, is positioned upon the flange G of washer F, and thus the curtain is held between the washers C and I.

L indicates an approximately U-shaped spring, the same being split at one end, as shown at M, this spring being adapted to be placed between the front face of the washer I and the rear portion of a cap N, which is provided with a central opening O, said cap N having formed integral with the rear portion of the legs P, said legs being adapted to pass through the spring, the slots K of the washer I, and then through the slots D of the washer C, so as to permit the free ends thereof being clenched on the rear portion of the washer C, thereby locking the several parts of the fastening device together and securely holding the curtain in place.

It will be observed that the prongs or feet P, formed integral with the rear portion of the cap N, pass through the open central portion of the spring L, so that said cap will serve as a retaining device to hold said spring in the desired position. Said spring is held in place by the end at the split M in such a manner as to permit of said spring being given a certain amount of play in order that

the knob or button will not draw the spring against the prong and thereby spread and weaken said spring.

In Fig. 6 I have shown a somewhat modified form of spring, in this instance the spring being provided with a ring portion Q, while the opposite ends thereof are split, as shown at R, it of course being understood that either of these forms of spring can be used 10 for the purpose intended.

From the foregoing description it will be seen that I provide a very simple and effective catch for curtains and that by reason of the peculiar arrangement of the several parts 15 described and the peculiar formation of the knob or button over which the curtain is passed I provide a fastening device possessing many advantages over the same class of devices of this character heretofore employed.

20 The device is very simple in construction, and by reason of the peculiar arrangement, as already set forth, any part of the fastening device can be easily removed in case of breakage or wear of the parts by simply turning up the prongs or feet of the cap or washer N and withdrawing the same from the slots of the washers C and I, when access can be had to any of the parts constituting the catch.

It is evident that various slight changes

might be made in the forms, constructions, 30 and arrangements of the parts described without departing from the spirit and scope of my invention. Hence I do not care to limit myself to the exact construction herein set forth, but consider myself entitled to all such 35 changes as might fall within the spirit and scope of my invention.

Having thus described my invention, what I claim as new, and desire to secure by Letters Patent, is—

40 The combination with an apertured curtain, of plates positioned on opposite sides of the curtain and apertured in line with the aperture thereof, said plates formed with a series of slots, a washer with flanges fitting in the 45 apertures of the plates and the curtain, a spring arranged across the aperture of the plates, and a retaining-plate having prongs which extend through the slots of the plates and are clenched on the back of one of the 50 plates, said prongs also extending through the open portion of the spring and retaining the same in position, substantially as shown and described.

HAYES YOUNG.
